Inventor:

William Roberts

United States Patent Office.

WILLIAM ROBERTS, OF FARNHAM, NEW YORK, ASSIGNOR TO HIMSELF,
AUSTIN ROBERTS, AND WELCOME SPRAGUE, OF SAME PLACE.

Letters Patent No. 79,007, dated June 16, 1868.

IMPROVEMENT IN CORN-SHELLER.

The Schedule referred to in these Letters Patent and making part of the same.

TO ALL WHOM IT MAY CONCERN:

Be it known that I, WILLIAM ROBERTS, of Farnham, in the county of Erie, and State of New York, (assignor to myself, Austin Roberts, and Welcome Sprague, of the same place,) have invented a certain new and improved Corn-Shell; and I do hereby declare that the following is a full, clear, and exact description thereof, reference being had to the accompanying drawings, making a part of this specification, in which—

Figure I is a vertical section, and.

Figure II is a top plan view.

The nature of this invention consists in supporting the journals of the roller or toothed drum within oval slots or recesses formed in the sides of the main frame, in combination with springs and blocks, the bottom of the recesses or slots, and the under side of the blocks, being of such shape and construction as to permit the roller or drum to yield not only upwardly, but also horizontally, accommodating itself to the varying thickness of the cobs to be shelled.

Letters of like name and kind refer to like parts in each of the figures.

A represents the toothed roller or drum, which may consist either of a metallic hollow cylinder, having the teeth cast on to its outer surface, or of a wooden solid cylinder, having the teeth driven into it like nails.

The teeth are arranged in rows, parallel with the axis of the roller, and placed about half an inch apart.

The journals of the roller are shown at a'. They rest in slots or recesses b', cut in the side frames B of the machine, which slots are wider than the diameter of the journals, so as to allow the latter to move horizontally therein.

Blocks C slide vertically within the slots, rest upon the journals, and are retained in their lowest position by means of the flat springs C', upon the top of the frames B, or by any other equivalent means.

The under side of these blocks C is of a concave shape, corresponding to the semi-oval shape of the bottom of the recesses or slots b'. The object of this peculiar construction is to allow the roller a short horizontal movement backward or forward, in addition to the vertical movement regulated by the springs c'.

D represents a grate, composed of a number of bars, placed parallel with the axis of the roller, between the two frames, and arranged semicircularly below the said roller, and in close proximity thereto.

E represents a plate extending between the frames, and from one end of the semicircular grate upwardly. This serves the purpose of a feeding-hopper.

F is a plate extending from the other end of the grate downwardly, and this is for carrying off the cobs after the corn has been shelled by the action of the toothed roller and the grate.

This improved corn-sheller is simple in its construction and operation, and may be set in motion by hand, dog, horse, or steam-power, as may be desired.

The corn is fed to the machine by placing it between the hopper-plate E and roller A. The teeth of the latter, while revolving the cob, and drawing it on to the grate D, enter between the kernels and pry them apart, loosening all the surrounding kernels at the same time. Hence, when the cob is passing over the sharp edges of the grate-bars, the kernels so loosened are scraped off, and fall between the grate-bars into a receptacle below.

The cobs, as they are forced around the drum and over the grate-bars, will not be broken, on account of the yielding movement of the drum, giving way to a cob of large dimensions, and returning to take hold of a small one.

The empty cobs are discharged over the hopper F.

This is one of the cheapest corn-shellers, as, besides doing its work correctly, it separates the corn from the cobs—a degree of perfection not heretofore attained, except in corn-shellers of more complicated construction.

I am well aware that corn-shellers have heretofore been invented and patented, comprising in their construction a roller or toothed drum, and a circular grate-bar, and I do not therefore claim such construction and combination as new; but

What I claim as my invention, and desire to secure by Letters Patent, is—

Supporting the journals a' of the toothed roller A within the slots or recesses b' , in combination with the blocks C and springs C', or their equivalents, when these parts are constructed and operating in the manner substantially as herein described.

WILLIAM ROBERTS.
